METHOD OF FILLING CONFINED SPACES
ASSOCIATED WITH ELECTRIC APPARATUS

Edwin Charles Lee, London W. C. 2, England, assignor to International Standard Electric Corporation, New York, N. Y.

Application October 2, 1940, Serial No. 359,400
In Great Britain April 10, 1940

9 Claims. (Cl. 174—22)

This invention relates to a method of filling confined spaces associated with electric apparatus.

The invention has particular reference to the problem of filling various spaces included within an outer covering with solid material, and is very useful in filling spaces around an electric power cable to form a barrier against the flow of insulating fluid, though by no means confined to such use. For such use it has previously been proposed to effect the filling by using a granular moulding powder and converting it into a solid by the application of heat and pressure. With such a method, however, considerable heat and pressure are necessary and it is difficult to eliminate the air between the particles of moulding powder before applying pressure and to secure a satisfactory bond between the moulding and the surrounding metal casing.

It has also been proposed to fill the spaces surrounding an electric power cable joint with a monomeric material such as monomeric styrene, and thereafter to thicken it by heating to cause it to polymerise. In this method the application of heat has to be extended over a period of many hours, since although the originally introduced styrene may be partially polymerised, it must be thin enough to flow in conveniently and displace all residual air in the spaces to be filled. Moreover, there is considerable contraction in cooling down from the polymerisation temperature usually 120° C.

According to the present invention a method of filling confined spaces associated with electric apparatus comprises filling the spaces with a fluid solvent for an extrudable material, and then displacing this solvent by forcing in the extrudable material under pressure to displace the fluid solvent.

As an example of an extrudable material, shellac may be mentioned; a suitable solvent therefor is methylated spirit. We prefer, however, to use as the extrudable material a polymerised material and in particular polystyrene, in which case the preferred solvent is monomeric styrene. Other monomers may be used such as methyl methacrylate, so long as they are compatible with the polymer, or alternatively a simple solvent such as benzene.

The extrudable material may be rendered more readily extrudable by the addition of plasticisers. For example, in the case of polystyrene, any well-known plasticiser may be used, or in the case in which the material is to be within an electric field, one of the plasticisers disclosed in U. S. 55

Patent No. 2,272,996, issued Feb. 10, 1942 may be used. The most suitable type of plasticiser is one which promotes a flat viscosity temperature characteristic, i. e. the extrudable material must not be too hard at 20° C. nor too soft at 100° C.

5 Filling with plasticised polystyrene or other polymers is facilitated by warming the material to a temperature of 100° C., although this is not generally essential, and a pressure of up to 1000 lbs. per square inch may be required depending upon the viscosity of the filling material and the shape of the space to be filled.

10 The invention is applicable to the filling of spaces within a casing surrounding a joint or 15 termination of an electric power cable in order to form a barrier joint or termination, and also to filling an electric transformer casing with an insulant.

15 The nature of the invention will be better understood from the following description of certain embodiments thereof taken in conjunction with the accompanying drawings in which:

20 Fig. 1 shows a cross sectional view of a barrier joint in a single core electric power cable suitable for use in a 33 kv. cable;

25 Fig. 2 shows a cross sectional view of a barrier joint for a 3-core belted type of power cable for use in a 66 kv. cable system; Fig. 2A shows a detail of Fig. 2; whilst

30 Fig. 3 shows a barrier type of termination for an electric power cable.

35 Referring to the drawings, Fig. 1 shows a form of barrier joint for a single core 33 kv. cable. The insulation is removed from the ends 3 and 4 of the two lengths of cable to be joined and a sleeve 7 is slipped over one of the ends. The lengths 1 and 2 are joined by means of a copper ferrule 5. The insulation from the two lengths of cable is tapered as shown at 1 and 2. The space shown at 6 is then filled up by building up the insulation with paper tapes impregnated with polystyrene and basting the impregnated tapes with monomeric styrene at intervals during the building up of the insulation to cause them to 40 adhere to one another as described, for example, in British Patent No. 504,720, accepted April 26, 1939. A layer 8 of metal foil is wound over this built up insulation and electrically connected to the lead sheaths 9, 10 of the two lengths of cable.

45 50 Lappings 11 of cotton tape impregnated with a mixture of rubber and polystyrene are applied over the ends of the layer 8 and overlapping the lead sheaths 9, 10, to prevent oil from flowing from the cable into the joint and solvent from flowing into the cable during the filling. The

sleeve 7 is then slipped back over the joint, lead packing 12 being inserted between the ends of the sleeve 7 and the lead sheaths 9, 10. The sleeve 7 is joined to the lead sheaths by plumb-wipes 13, 14.

The sleeve 7 is provided with a filling plug 17 and outlet plugs 15, 16. Monomeric styrene is fed into the plug 17 until the space 18 between the earthed screen 8 and the sleeve 7 is completely filled therewith. Polystyrene, plasticised in accordance with the aforementioned U. S. Patent No. 2,272,996, is then fed under pressure into the filling plug 17. Precautions must also be taken that the polystyrene is free from bubbles. Pressure is continued until the material issuing from the outlet plugs 15, 16 is of the thick consistency of the plasticised polystyrene. The joint is then completed by sealing the plugs. In this example it should be noted that the electrical properties are unimportant; the material merely serves as a mechanical barrier.

Fig. 2 shows the invention applied to a barrier joint for a 3-core belted type of cable. The belting is removed from a certain distance from the ends to be joined and a sleeve 7 slipped over the lead sheath of one of the lengths. The ends of the three cores are joined by copper barrier ferrules 5. The three cores are spaced apart by spacers 19 shaped as shown in Fig. 2A, the cores being bound thereto. The spacers are suitably made of compressed styrenated paper. Cotton tapes 21 impregnated with a mixture of rubber and polystyrene are wrapped around the cables overlapping the lead sheath in order to prevent egress of oil from the cable and flow of solvent into the cable during formation of the barrier joint. The sleeve 7 is then slid over the joint, spaced from the lead sheaths 9 and 10 by lead packing 12 and sealed by wiped joints 13 and 14. The sleeve 7 is then filled with monomeric styrene through the plug 17 and when it is full the monomeric styrene is displaced by plasticised polystyrene fed into the plug 17 in the same manner as described with reference to Fig. 1. In this example the filling material acts both as a mechanical barrier and as the main insulant of the joint.

Fig. 3 shows a barrier type of termination formed according to the invention. A preformed cylinder 22 of insulating material and of sufficient diameter to be slipped over the insulation 25 of a cable core is provided with metal end caps 23, 24, securely cemented to the cylinder 22 and of sufficient diameter to extend over the lead sheath 10 of a cable. The lead sheath 10 is removed for some distance from the end of the cable; the metallised paper 26, which usually covers the insulation, is stripped off up to a short distance from the lead sheath 10 and the insulation 25 is removed for a short distance from the end and bound as shown at 27. A copper end ferrule 5' is soldered to the conductor 28. The cylinder 22 is then slipped over the cable end, and the metal cap 24 pressed down on the lead sheath 10 and joined thereto by a wipe 13. The cap 23 is then sweated on to the stalk of the ferrule 5'.

The cap 24 is provided with a filling plug 17 and the cap 23 with a vent plug 15. The spaces within the cylinder 22 are then filled as above described with reference to Fig. 1 or Fig. 2.

It will be evident that the present invention is applicable to a number of different types of joints and terminations in electric power cables. It is, however, to be noted that the invention is

not limited to use with power cables, but is applicable to any case in which confined spaces associated with electric apparatus are to be filled with solid material and only restricted openings are available through which the filling material can be introduced. Thus the invention may be applied to form a body of insulating material within a metal casing surrounding an electric transformer, being particularly useful in the case of a transformer used for high voltages and high frequencies, or to form the dielectric of a multiple plate condenser contained within a casing.

The fluid first fed into the casing acts as a lubricant and also as a wetting agent which facilitates filling and secures thorough bonding between the plasticised polymerised material, such as polymerised styrene and both metal surfaces and oil impregnated cable papers. The polymerised material then fed in has an excellent barrier action and, more particularly in the case of polystyrene, excellent insulating properties, high breakdown strength and low power factor.

What is claimed is:

- 25 1. Method of filling spaces within a container associated with electrical apparatus with insulating material, which comprises filling the said spaces with a fluid solvent for an insulating extrudable material, and then displacing the said solvent by the said extrudable material.
- 30 2. Method of filling spaces within a container associated with electrical apparatus with insulating material, which comprises filling the said spaces with a fluid solvent for polystyrene, and then displacing the said solvent by polystyrene.
- 35 3. Method as claimed, in claim 2 in which the said solvent is monomeric styrene.
- 40 4. Method of filling spaces within a container associated with electrical apparatus with insulating material, which comprises filling the said spaces with a fluid solvent for polystyrene, and then forcing polystyrene into said spaces under pressure to displace the said fluid solvent.
- 45 5. Method of filling spaces within a sleeve surrounding a barrier in an electric power cable, which comprises filling the said spaces with a fluid solvent for polystyrene, and then forcing polystyrene into said spaces to displace the said fluid solvent.
- 50 6. Method of forming a barrier joint between two lengths of sheathed electric cable, which comprises joining the cores of the two cables together, building up a body of insulation around the joined cores by winding therearound tapes comprising polystyrene, and basting the tapes during the winding with a solvent for polystyrene, surrounding said built-up insulation with a sleeve, welding said sleeve to the cable sheaths, filling spaces within said sleeve with a solvent for polystyrene, and forcing polystyrene into said sleeve until said last mentioned solvent is almost completely displaced.
- 55 7. Method of forming a barrier joint between two lengths of multi-core sheathed electric power cable, which comprises joining the several cores of one length to the several cores of the other length, spacing apart and supporting the jointed cores by solid insulating spacing members, surrounding said members and said jointed cores by a covering sleeve, bonding said sleeve to the sheaths of the two cable lengths, filling the space within said sleeve with a solvent for polystyrene, and forcing polystyrene into said sleeve until said solvent is almost completely displaced.
- 60 8. Method of forming a barrier termination

for an electric power cable, which comprises joining the end of the core of said cable to an end ferrule, surrounding said joint by a preformed casing, welding said casing to the sheath of said cable and to the said ferrule, filling said casing with a solvent for polystyrene, and forcing polystyrene into said casing until said solvent is almost completely displaced.

9. Method of forming a barrier joint between

two lengths of sheathed electric cable, which comprises joining the cores of the two cables together, surrounding the joint thus produced with a sleeve, sealing said sleeve to the cable sheaths, filling spaces within said sleeve with a solvent for polystyrene, and forcing polystyrene into said sleeve until said solvent is substantially completely displaced.

EDWIN CHARLES LEE.
